UNITED STATES PATENT OFFICE

ENGELBERT ZASCHKA, OF BERLIN-NEUKOLLN, GERMANY

HELICOPTER

Application filed June 29, 1927, Serial No. 202,196, and in Germany June 18, 1926.

This invention relates to an improved helicopter in which the lifting propeller and a gyrating fly-mass are continually connected with one another in rotation and can be coupled with the driving propeller in order to drive it as a substitute for the motor if this latter should have got out of order from any reason. This is very important if the defect in the motor arises, perhaps, just while the helicopter is flying over a swampy country where landing would be disastrous. There is only one motor in this helicopter, and there are couplings provided by which the motor can be connected either solely with the lifting propeller and the fly-mass, or solely with the driving propeller or with the lifting propeller and the fly-mass, as well as with the driving propeller, or by which, finally, the lifting propeller and the fly-mass can be connected with the driving propeller, as already mentioned.

The thus designed helicopter is illustrated diagrammatically and by way of example on the accompanying drawings on which Figure 1 is a side-view, Figure 2 a plan thereof, and Figure 3 is a plan-view of the car, supporting planes being omitted.

The car h which may be of the usual design is provided with an upwardly directed cylindrical extension h' , upon the top face of which is supported a central portion g' which is rotatable around its vertical axis. From this central portion extend horizontally in opposite directions the supporting planes g which, as regards their angle of inclination, are adjustable on horizontal pivots r extending forth from said portion g' . I have abstained from showing the means for varying the pitch of the (propeller-forming) supporting blades because these means are known and do not form parts of the present invention. a denotes the motor in it, and k the driving propeller which is preferably horizontally turnable or adjustable, as appears from the different positions of this propeller in the two figures. The driving power is transmitted from the motor to the propeller k by means of a shaft j into which are inserted two couplings b^1 and b^2 . Between these

el-wheel c which forms a member of a bevel-wheel gearing, the other member of which is secured to a vertical shaft e extending upwardly through the helicopter frame, on the top of which is located the lifting propeller g which is of the variable pitch type, as is indicated by the pivots r in Fig. 2

It has already been said in the introductory part to this specification that the lifting propeller and the gyrating fly-mass are continually connected with one another in rotation. In the example shown in the drawings the direction of rotation of the said lifting propeller and the said fly-mass is opposite to one another. This is indicated in Fig. 2 by the arrows. d denotes said fly-mass which is arranged above the propeller g and is affixed to the upper end of the shaft e . There is in the frame g' of the helicopter another shaft n to which cog-wheels m and o of different size are affixed. The cog-wheel m meshes with a smaller cog-wheel i secured to the shaft e , and the cog-wheel o meshes with a larger gear-wheel rim p firmly connected with the portion h' of the car h by means of screws x (Fig. 3).

When the shaft e is rotated, the auxiliary shaft is turned by the intermediary of the cog-wheels i and m , and the wheel o runs round the stationary gear-wheel rim p , whereby the portion g' is rotated, as are also the supporting planes g .

There is in the shaft e also a coupling b^2 by means of which the fly-mass and the lifting propeller can be disconnected from the shaft j , or from the motor a respectively, so that the machine can run on the ground without consuming power for the members d and g . On the other hand, the kinetic energy stored in the rotating members d and g can be utilized for driving the propeller k for a certain while if the motor is, from any reason, not able to do that. This utilization can be very important if the machine is over swampy ground.

When the helicopter is to rise and the motor has attained that number of revolutions which is required therefor, the supporting planes are suitably turned on the pivots r so that they form and act as a propeller.

I—I (Fig. 2) denotes the axis on which the planes or blades g are turned. This is effected from the pilot's seat by a suitable transmission gear, for instance rods, cables, 5 or the like. The planes or blades are turned, of course, in the positive direction, in which they act lifting.

Driving the helicopter horizontally is effected by the propeller k which is driven by 10 the motor a by means of the shaft j . Controlling this propeller is effected by turning it on the axis II—II (Fig. 1) which may be effected from the pilot's seat by any suitable known transmission gear.

15 When the machine is to descend, first the motor is stopped, the coupling b^2 is uncoupled, and then the planes or blades g are adjusted for negative action. The machine is now descending or sinking respectively, 20 but as the blades g are subjected to the counter-acting pressure of the air they are rotated by the air and with them also the gyratory mass d is rotated, the direction of this rotation being counter to the direction of 25 rotation of the blades g , so that a certain amount of kinetic energy is accumulated in said mass. The amount of this energy depends upon the velocity of the downward movement of the machine. The greater the 30 negative (angle of) pitch, the larger is the amount of the kinetic energy stored in the gyratory mass. Shortly prior to the landing, the blades g are again adjusted to the positive (angle of) pitch in which they retard 35 the downward movement of the machine until it becomes zero, the blades being rotated during this time by the energy stored in the rotating mass d . Also the propeller k can be rotated during that time by the mass d , in 40 that the shaft e (the coupling b^1 being uncoupled at this time) is coupled by the coupling b^3 with the propeller k .

I claim:

1. A helicopter, comprising, in combination with the car, the motor therein, the driving propeller, and the means for transmitting the power to it, a lifting propeller, the blades of which are adapted to act like supporting planes, a fly-mass gyrating in a plane parallel to the plane of motion of said lifting propeller, a gearing by which this propeller and said mass are continually connected with one another in rotation, means for transmitting power from said motor to the said fly-mass and, by the medium of said gearing, to the said lifting propeller; and a coupling so arranged as to permit disconnecting the fly-mass and the lifting propeller from the motor.
2. A helicopter, comprising, in combination with the car, the motor therein, the driving propeller, and the means for transmitting the power to it, a lifting propeller, the blades of which are adapted to act like supporting planes, a fly-mass gyrating in a plane

parallel to the plane of motion of said lifting propeller, a gearing by which this propeller and said mass are continually connected with one another in rotation, means for transmitting power from said motor to the said fly-mass and, by the medium of said gearing, to the said lifting propeller; and a coupling so arranged as to permit disconnecting the fly-mass and the driving propeller from the motor.

3. A helicopter, comprising, in combination with the car, the motor therein, the driving propeller, and the means for transmitting the power to it, a lifting propeller, the blades of which are adapted to act like supporting planes, a fly-mass gyrating in a plane parallel to the plane of motion of said lifting propeller, a gearing by which this propeller and said mass are continually connected with one another in rotation, means for transmitting power from said motor to the said fly-mass and, by the medium of said gearing, to the said lifting propeller; and a coupling so arranged as to permit disconnecting the fly-mass and the driving propeller from the motor without interrupting the power-conducting connection between this propeller and the said fly-mass, as well as the lifting propeller, substantially and for the purpose as set forth.

In testimony whereof I have affixed my signature.

ENGELBERT ZASCHKA.
